(57) **CLAIM**

The ornamental design for a reamer assembly as shown and described.

DESCRIPTION

FIG. 1 is a front isometric view of a reamer assembly; FIG. 2 is a rear isometric view thereof;

FIG. 3 is a top view thereof;

FIG. 4 is a side view thereof;

FIG. 5 is a bottom view thereof;

FIG. 6 is a front view thereof; and,

FIG. 7 is a rear view thereof.

The broken lines in the drawings illustrate portions of the reamer assembly that form no part of the claimed design.

1 Claim, 4 Drawing Sheets
